UNITED STATES PATENT OFFICE.

JOSEPH HREN, OF KINGSTON, NEW YORK

SLICING AND WRAPPING MACHINE.

1,171,439.

Specification of Letters Patent. Patented Feb. 15, 1916.

Application filed August 17, 1915, Serial No. 45,997.

To all whom it may concern:

Be it known that I, JOSEPH HREN, a citizen of the United States, and a resident of Kingston, county of Ulster, and State of New York, have invented certain new and useful Improvements in Slicing and Wrapping Machines, of which the following is a specification.

This invention relates to a machine of novel construction more particularly adapted for subdividing an article in bulk such as ice cream into a plurality of blocks, subdividing the blocks into slices, and folding wrappers around the top and bottom and sides of such slices.

Briefly stated, a series of severed paper webs are drawn by a carriage to a position underneath a hopper within which the article to be sliced is divided up into blocks. The carriage is furnished at its rear end with a cutter, at its front end with a gripper, and with a trough-shaped container between cutter and gripper. The gripper so holds the webs that they bridge the container, and after the wrappers have been severed from the webs by the cutter, the carriage moves with its container and the superposed wrappers to the hopper. Here the sliced portions of the blocks drop into the container so as to carry the wrappers with them and fold them around the two sides of the slabs. Upon the subsequent return movement of the carriage, the upper flap of the wrapper is folded over the top of the slab when the operation is completed.

In the accompanying drawing, Figure 1 is a plan, partly broken away, of a slicing and wrapping machine embodying my invention; Fig. 2 a side elevation; Fig. 3 a perspective view of a package cut and wrapped by the machine; Figs. 4, 5, 6, 7 and 8 are longitudinal sections of the principal parts of the machine, showing consecutive positions of the carriage; Fig. 9 an end view of the paper cutting device; Fig. 10 a side view of parts thereof; Fig. 11 a vertical cross section of Fig. 10; Fig. 12 a cross section through the gripper; Fig. 13 a longitudinal section through the hopper showing the slab and cutter in side view; Fig. 14 a perspective view of one of the hopper-partitions, and Fig. 15 a detail of one of the cams.

The frame A of the machine is supported on legs B, and is provided with grooved

ways 1, engaged by a slide or carriage 2. This carriage is adapted to be reciprocated in said ways by crank handle U, shaft 3 and pinions Z that engage racks J of the carriage.

The carriage is provided with a transversely extending trough 4, which is of rectangular shape in cross section and is adapted to receive the sliced material to be wrapped. In advance of said trough, the slide is provided with a gripper which is adapted to grasp the ends of a plurality of parallel paper strips or webs F drawn from a common reel C over a guide rod 5 and thence over a fixed table 6, and beneath a tension device D' and a guide rail m' m' arranged at the end of the table. After clearing the table, webs F extend across the top of carriage 2, so as to bridge trough 4 and are thence engaged by the gripper. Back of trough 4, carriage 2 is provided with a cutter adapted to sever simultaneously the several webs F after the same have been drawn forward by the carriage a distance sufficient to form wrappers of the required length.

The cutter is illustrated more fully in Figs. 9-11, and consists of a lower relatively fixed cutter bar J', and an upper movable cutter bar D. Lower bar J' is provided with a central longitudinal groove and with a pair of flanking grooves containing cushioning tubes g. Upper bar D is movable in slotted upright posts p of carriage 2 and is provided with a blade e adapted to enter central groove of bar J', and with a pair of resilient clenching jaws f adapted to be lowered upon cushions g so as to grip the webs F during the cutting operation. In order to guide bar D along posts p it is provided with rollers n, while springs r tend to raise the bar within the posts.

Bar D is operated in the following manner:—From frame A extend upwardly a pair of posts 7 to which are pivoted by shaft b, a pair of notched cams H. Each cam is adapted to be held in its inactive horizontal position by a conical pin c c housed within a bore of the cam and pressed into a notch of shaft b by a spring d d and screw e e. From posts p project a pair of pins W which are adapted to engage the operative cam edges. During the forward movement of carriage 2 these pins will swing the cams downward (or into the position shown in

Fig. 15) whereby the bar is depressed to 5 clench webs F by jaws f and to sever the same by blade e. After the pins W have swung the cams into a vertical position, they will clear the same, so that bar D becomes liberated and may be raised by springs r, while the cams will be arrested by pins p' and will subsequently be returned to their horizontal position by pins W upon the next 10 return movement of the carriage.

The gripper that takes the webs along on the forward movement of carriage 2, comprises essentially a movable jaw X adapted to coöperate with a relatively fixed 15 jaw 8 formed at the forward edge of carriage 2 and furnished with a cushioning tube h. Jaw X is hinged to jaw 8, at 9 and is influenced by a spring j. From jaw X depends a tail piece 10, which is adapted to be 20 engaged by a tappet K pivoted at 11 to the body of the carriage, and adapted to be swung up by a fixed shaft or abutment k. When the carriage is moved to the left, a head K' of tappet K will by abutment k 25 be raised against tail piece 10, so as to open jaw X (Fig. 12) and cause the same to receive the ends of webs F. The further movement of the carriage to the left will cause head K' to clear abutment k, whereby 30 the tappet will drop and cause jaw X to be closed by spring j so as to grasp the webs. As the carriage is next moved to the right, the jaws will draw the webs along with them, so as to reel off the proper 35 lengths for forming the wrappers, which lengths are determined by the length of the slide race. When the carriage has arrived at or near the end of its race, cutter bar D is lowered in manner hereinbefore described 40 to sever from the webs, the lengths of paper, for forming said wrappers. As has been stated, the carriage must move some distance to the left or toward table 6, after its jaw X has grasped the end of the webs 45 for the purpose of closing the jaw. In order to support the end of the webs along the gap required for such movement, there is provided a slidable platen m m adapted to move underneath table 6 and to be alternately projected and retracted from the 50 forward edge thereof by the movement of the carriage. To operate this platen there is provided a rock shaft 12 having arms f f hingedly connected to the left end of platen 55 m m. From arms f extend forwardly a pair of rods g g passing through a guides 13 of carriage 2, and carrying nuts or other adjustable abutments 14 at their free ends. As carriage 2 is about to complete its stroke 60 to the left, it will strike arms f f and thus cause the latter to move platen m m to the left. In this way the gap is opened up at the right edge of table 6, which permits the carriage to complete its movement to 65 the left and grasp the webs. The carriage

will then move to the right as previously described, and during this movement the guide 13 will eventually strike abutments 14 and thus move platen m m to the right so as to close the gap and support webs F. 70 The ice cream or other article to be sliced and wrapped is introduced into a hopper T which is provided near its top with a hinged shelf m upon which the ice cream to be divided is placed in bulk. As this shelf is 75 swung up, the mass will be dropped into a chamber arranged in the upper end of the hopper and which is of a size to receive the same. Below such chamber, the hopper is divided into a plurality of compartments 80 or chutes separated from each other by partitions b. Each of these partitions is received in corresponding grooves of the hopper wall and is held in position by a set screw u, so that the partitions may be 85 readily removed and reset. At the top of each partition is formed a cutter head a which is somewhat wider than the partition, so that the ice cream after being cut into blocks will have a clearance and will not 90 be apt to adhere to the sides of the partitions but will freely drop down through the chutes. Through the upper chamber of the hopper there is free to move a plunger x which on being lowered forces the mass 95 against the knives. Plunger x is operated by crank handle 15, and pinions P, that engage racks 16 depending from the plunger, said racks being also engaged by pawls s that serve to sustain the plunger in its 100 raised position.

At the bottom of the hopper there is fitted a horizontally movable slicing blade t, carried by a slide 17 which is provided with guide rollers v moving in corresponding ways of frame A. Slide 17 is reciprocated by crank handle V, shaft 18, pinion Q and racks O. A tapering finger R extending from slide 17 over a pin z of frame A, is adapted to be projected under a pin 110 19 extending laterally from jaw X. Thus upon the movement of slide 17 to the right, finger R will by pin 19 tilt jaw X, so as to liberate webs F, from carriage 2. In order to permit the machine to be thoroughly 115 washed it is provided with a drip pan M, having pet cocks a a.

The operation is as follows: The ice cream or other body to be sliced and wrapped is from shelf m dumped into hopper T, and 120 then the plunger x is lowered to force said body against cutters a, and cause it to fall in blocks through the various chutes upon slicing blade t. Carriage 2 after having by jaw X grasped the various paper webs 125 during the latter part of its return stroke, is moved to the right, (Fig. 4) to thus carry the webs a distance beyond the right edge of table 6. As soon as the pins W of the carriage come, during this movement, into en- 130

gagement with cams H, they will cause cutter bar D to descend (Fig. 5) so that the wrappers are cut off the webs. Upon the further movement of the carriage to the right, the several wrappers thus formed, and which will bridge trough 4, will arrive underneath hopper T (Fig. 6). The slicing blade t upon which the ice cream has been supported is now reciprocated to sever a slice or slab 20 off each block and cause it to drop by gravity upon the wrapper. The weight of the slice will thus cause it to drop into the former 4, and to take the wrapper 21 along with it, so that in this way the 15 wrapper will be made to infold the bottom as well as two sides, but not the ends of the slice. If desired a false bottom or compensating block 22 may be placed into trough 4 by means of which the thickness of the cut 20 off slice may be regulated. After the slice has dropped into the former, carriage 2 is moved to the left, during the beginning of which movement the upper flap of the wrapper will encounter a roller I of frame A by 25 means of which such flap will be folded over the top of the slice, (Fig. 7). The inwrapped slab is then lifted out of the carriage and the latter continues its movement to the left (Fig. 8), so that jaw X will be 30 opened and will reengage webs F, whence the operation is repeated.

I claim:—

1. A machine of the character described, comprising a hopper adapted to receive a charge to be sliced and wrapped, means for slicing said charge, a carriage adapted to receive the sliced charge, and wrapper-gripping means on the carriage.

2. In a machine of the character described, 40 a carriage having a container, web-cutting means at one side of the container, and web-gripping means at the other side of the container, combined with a hopper, means for moving the carriage beneath the hopper, and 45 a blade adapted to be projected across the hopper and above the carriage.

3. In a machine of the character described, 50 a table adapted to receive a plurality of webs, a hopper, a carriage adapted to reciprocate intermediate said table and hopper, a container in the carriage, and web cutting means and web gripping means arranged on opposite sides of the container.

4. In a machine of the character described, 55 a table adapted to receive a plurality of

webs, a carriage having a container, a movable platen, adapted to extend the table, and means operable by the carriage for extending or retracting said platen.

5. In a machine of the character described, 60 a table adapted to receive a plurality of webs, a carriage having a container, a platen slideable beneath the table, a shaft, arms on the shaft, rods on the arms and abutments on the rods, said arms and abutments being 65 adapted to be engaged by the carriage.

6. In a machine of the character described, 70 a carriage having a container, a fixed gripper jaw, a spring-influenced movable gripper jaw hingedly connected to the fixed jaw, a tail piece on said movable jaw, and a tappet hinged to the carriage and adapted to engage said tail piece.

7. In a machine of the character described, 75 a carriage having a container, a fixed gripper jaw, a spring-influenced movable gripper jaw, a tail piece on the movable jaw, a tappet having a head and hinged to the carriage, said tappet being adapted to engage the tail piece, and an abutment adapted to 80 engage said tappet.

8. In a machine of the character described, 85 means for dividing a mass into blocks, means for slicing said blocks into slabs, a carriage having a slice-receiving container, means for supporting wrappers across said container, and means for moving the carriage toward and away from the slicing means.

9. In a machine of the character described, 90 means for dividing a mass into blocks, means for slicing said blocks, a carriage, means on said carriage for grasping a plurality of paper webs, means also on the carriage for severing said webs, and means for moving 95 the carriage toward and away from the slicing means.

10. In a machine of the character described, 100 means for slicing a mass, a carriage having a container adapted to be projected beneath said slicing means, means on the carriage for sustaining a series of wrappers that are adapted to bridge the container, means for retracting the slicing means and thereby causing the sliced mass to drop together with the wrapper into the container, and means actuated by the return movement of the carriage for folding the wrapper over 105 the top of the sliced mass.

JOSEPH HREN.
